CLAIM

The ornamental design for a combined dispenser for sanitary paper and bracket, as shown and described.

DESCRIPTION

FIG. 1 is a rear perspective view of a combined dispenser for sanitary paper and bracket showing my new design;

FIG. 2 is a right side elevational view thereof, the left side being a mirror image.

FIG. 3 is a top plan view thereof;

FIG. 4 is a bottom plan view thereof;

FIG. 5 is a front elevational view thereof;

FIG. 6 is a rear elevational view thereof;

FIG. 7 is a top perspective view of the dispenser shown separate for clarity of illustration;

FIG. 8 is a side elevational view of FIG. 7.
